United States Patent Office.

JAMES WRINKLE, OF LEE, MASSACHUSETTS.

Letters Patent No. 85,157, dated December 22, 1868.

IMPROVED MACHINE FOR MIXING COLORING-MATTER WITH PAPER-PULP.

The Schedule referred to in these Letters Patent and making part of the same

To all whom it may concern:

Be it known that I, JAMES WRINKLE, of Lee, in the county of Berkshire, and State of Massachusetts, have invented a new and useful Improvement in Paper-Making Machinery; and I do hereby declare that the following is a full, clear, and exact description thereof, which will enable those skilled in the art to make and use the same, reference being had to the accompanying drawings, forming part of this specification.

This invention relates to a new and useful improvement in paper-making machinery, and has for its object the prevention of the blue spots and lumps being formed or made in the paper during the process of manufacture, a result due to the blue coloring-matter which is placed in the pulp, and the adhering together of certain fibres or particles of the same.

In the accompanying sheet of drawings—

Figure 1 is a plan or top view of my invention.

Figure 2, a vertical section of the same, taken in the line *x x*, fig. 1.

Similar letters of reference indicate corresponding parts.

A represents a vat, which may be of rectangular or other form, and

B is a screen placed over the vat, and connected at one end to the top of the same by joints *a a*.

These parts being of usual construction, do not require a minute description.

C C' are two narrow compartments at one end of the vat, communicating with A by means of an opening, *b*.

D is a pump of the rotary or fan kind, which communicates with the compartment C by means of a pipe, E; and

F is an eduction-pipe, which communicates with the

fan-pump and the compartment C', as shown clearly in fig. 1.

The pulp is placed on the screen B, and passes through the same into the vat A, the usual amount of blue coloring-matter being put into the pulp.

The latter passes through the opening *b* into the compartment C, from whence it is drawn out by the pump D, and forced into the compartment C'.

The pulp passes from the compartment C' through an opening, *c*, upon the ordinary wire cloth, (not shown,) where the drying-process and sheet-forming process are gone through with.

By thus taking the pulp from the vat, and forcing or pumping it into a compartment, from whence it passes upon the wire cloth, all lumps and blue spots are avoided, as the pulp and coloring-matter are kept well mixed, the fibres or particles of the pulp prevented from uniting or forming into lumps; and, if necessary or desired, a small grinding-apparatus may be connected with the pump, in order to still further comminute, grind, or mix the pulp and coloring-matter. With the use of a rotary or fan-pump, however, I do not deem this necessary.

I claim as new, and desire to secure by Letters Patent—

The drawing of paper-pulp from the vat and ejecting it into the compartment, from which it passes upon the wire cloth by means of a pump, rotary or reciprocating, substantially as and for the purpose herein set forth.

JAMES WRINKLE.
